UNITED STATES PATENT OFFICE.

JOHN F. O'CONNOR, OF CHICAGO, ILLINOIS, ASSIGNOR TO WILLIAM H. MINER, OF CHAZY, NEW YORK.

ROCKER SIDE BEARING.

1,268,993.

Specification of Letters Patent. Patented June 11, 1918.

Application filed February 26, 1917. Serial No. 151,004.

To all whom it may concern:

Be it known that I, JOHN F. O'CONNOR, a citizen of the United States, residing at Chicago, in the county of Cook and State of Illinois, have invented a certain new and useful Improvement in Rocker Side Bearings, of which the following is a full, clear, concise, and exact description, reference being had to the accompanying drawings, forming a part of this specification.

This invention relates to improvements in rocker side bearings.

One object of the invention is to provide a rocker side bearing of simple and efficient construction and so arranged that the rocker, which is loosely seated within a housing, is returned to normal position after each actuation, under the influence of gravity, the parts being provided with means positively insuring the return of the rocker to proper position after each movement.

The invention furthermore consists in the improvements in the parts and devices and in the novel combinations of the parts and devices, herein shown, described or claimed. In the drawing forming a part of this specification, Figure 1 is an end elevation of portions of a body and truck bolster of a car, showing my improvements applied thereto. Fig. 2 is an enlarged vertical sectional view of the side bearing proper and taken substantially on the line 2-2 of Fig. 1. Figs. 3 and 4 are transverse vertical sectional views of the side bearing and taken on the lines 3-3 and 4-4 respectively of Fig. 2. And Fig. 5 is a view similar to Fig. 3 illustrating a different embodiment of the invention.

Referring first to the structure as illustrated in Figs. 1, 2, 3 and 4, 10 denotes a body bolster of a car to which is pivotally connected in the usual manner a truck bolster 11. The body bolster, on each side of the king-pin, is provided with a bearing surface 12 and the improved side bearing, designated generally by the reference A, is preferably applied to the truck bolster.

The side bearing A, as shown in the drawing, comprises a base casting or housing B and a rocker C loosely mounted therein. The housing B is provided with a lower wall 13 having lateral extensions 14 by

which it is riveted to the bolster, oppositely curved end walls 15-15 and parallel side walls 16-16. The base of the casting is cut away, as indicated at 17, to receive combined wear and bearing plates 18-18, the latter being inserted through a suitable recess 19 in one of the end walls, the plates being held in by any suitable means such as the pin or key 20. The rocker C is of substantially polygonal form and comprises three series of opposed concentric bearing surfaces 21 and 121. Each of the bearing surfaces 21 is relatively small and is struck on a short radius, whereas the corresponding opposed bearing surface 121 is much longer and struck on a longer radius but from the same center. Each bearing surface 21 is disposed between a pair of bearing surfaces 121 and merges with the latter so that the rocker may be said to be of substantially triangular form. By making the opposed bearing surfaces concentric, as above described, it is apparent that as the rocker is moved or rolled from normal position, the vertical distance between the bearing 12 of the body bolster and the bearing surface of the upper plate 18 will remain constant. At each end, the rocker C is provided with an extension 22, the same being formed with three inwardly extending curved surfaces 122-122 and three outwardly extending curved surfaces 123, the projections being also of substantially triangular shape but with the horizontal side of the triangle uppermost whereas the corresponding side of the rocker C is lowermost, in normal position of the parts. The side walls 16-16 of the housing are each provided with a ledge or guiding shelf 24, the curvature of the latter being determined so as to correspond with the various positions of the inwardly extending curved surfaces 122 of the projection 22. In other words, the guiding ledge 24 may be said to be generated in the manner of a cycloid but instead of using a point, the two lowermost arcuate surfaces 122 of the lugs 22 are used.

The normal position of the parts is as shown in Fig. 2. Upon relative movement between the bolsters, the rocker C will be rolled to either end of the housing and the curved end walls 15 of the latter will serv-

as limiting stops for the rocker, as indicated by the dotted position of the rocker in Fig. 2. As the rocker moves to either side of its normal position, it will be apparent that the lugs 22 will then assume a position of unstable equilibrium so that said lugs 22 will act as eccentric weights on the rocker C to insure the return of the latter to normal position under the influence of gravity. Not only do the lugs 22 serve the function above described, but the same in conjunction with the guiding and positioning curved ledges 24, will positively insure the proper positioning of the rocker when it is returned to normal since the relation between the surfaces of the lugs 22 and the ledges 24 is such as to positively determine the position of the rocker C at any point in the rolling movement of the latter relatively to the base casting. In order to prevent any binding of the parts, a slight clearance is permitted between the lugs 22 and the ledges 24 but aside from this permissible clearance, the position of the rocker is positively determined relatively to the base casting or housing at all times.

On their inner faces at the center thereof, each of the side walls 16 may be provided with an inwardly extending projection 25 so as to prevent accidental disengagement of the rocker from the housing when the parts are in normal position. The rocker is inserted and removed from the housing when the lugs 22 are to one side of the projections 25, or, as indicated in the dotted position in Fig. 2, wherein the rocker may be removed by lifting the same vertically. The side walls of the housing may also be recessed, as indicated at 26, to prevent the accumulation of dirt or other foreign matter in the bottom of the side bearing.

In the construction illustrated in Fig. 5, the arrangement of the parts is the same as illustrated in the other figures except that a detachable pin 27 is passed through the center of the rocker and engages in suitable grooves 28 in the side walls of the housing to prevent disengagement of the rocker from the housing and no one of the plates 18 is removed. It will be understood that the pin 27 is applied when the rocker is at one of its extreme positions when the perforation in the rocker will be positioned

opposite a corresponding perforation in one of the side walls.

I claim:

1. In a side bearing, the combination with a housing, of a polygonal shaped rocker loosely seated within the housing, and co-operating means on said rocker and housing for properly and positively guiding said rocker to normal position after each actuation thereof, said means including non-circular lugs on the ends of the rocker and correspondingly outlined guiding ledges on the housing. 60

2. In a side bearing, the combination with a housing, of a rocker mounted within the housing, said rocker having a series of opposed concentric bearing surfaces to thereby maintain the distance between the bolsters or other parts to which the bearing is applied, constant, and co-operating means integrally formed on said rocker and housing for properly and positively positioning 70 said rocker in normal position after each actuation thereof, said means including a non-circular shaped lug on one end of the rocker adapted to itself act as an eccentric weight for the rocker when the latter 80 is displaced and to thereby return the rocker to normal under the influence of gravity.

3. In a side bearing, the combination with a housing, of a rocker loosely mounted within the housing, the rocker being provided at each end thereof with substantially triangular shaped lugs having curved sides, and the adjacent walls of the housing having guiding ledges, the outlines of which are generated substantially in the manner of a 85 90

cloud by said lugs.

4. In a side bearing, the combination with a hollow housing adapted to be secured to a bolster, of a rocker loosely mounted within said housing, said rocker having a series of opposed concentric bearing surfaces, the rocker having at each end thereof a non-circular projecting lug, and the adjacent walls of the housing being provided with guiding ledges co-operable with said lugs to 100 positively determine the position of the rocker.

In witness that I claim the foregoing I have hereunto subscribed my name this 15th day of Feb., 1917.

JOHN F. O'CONNOR.
